COMBINED HOLDER FOR A CAMERA AND LIGHTS

Louis Vicker, Chicago, and Jordan Lippman, Skokie, Ill.,
assignors to Harwood Electronics Co., Inc., Chicago,
Ill., a corporation of Illinois

Application May 29, 1959, Serial No. 56,139

Term of patent 14 years

(Cl. D61—1)

Fig. 1 is front elevational view of a combined holder for a camera and lights showing our new design;

Fig. 2 is a side elevational view thereof as viewed from the right in Fig. 1; and

Fig. 3 is a rear perspective view thereof.

The dominant features of our new design are shown in solid lines in the drawing, the broken line fragmentary showing of a light cord being for illustrative purposes only.

We claim:

The ornamental design for a combined holder for a camera and lights, substantially as shown.
